COMBINED CIGARETTE EXTINGUISHER
AND HANDLE FOR AN ASH RECEIVER

Douglas C. MacNally, San Jose, and Lawrence S. Berdahl, Sunnyvale, Calif.; said MacNally as signor to said Berdahl

Application January 29, 1952, Serial No. 18,284

Term of patent 14 years

(Cl. D85—8)

To all whom it may concern:

Be it known that we, Douglas C. MacNally and Lawrence S. Berdahl, citizens of the United States and residents of the county of Santa Clara, State of California, have invented a new, original, and ornamental Design for a Combined Cigarette Extinguisher and Handle for an Ash Receiver, of which the following is a specification, reference being had to the accompanying drawing, forming part thereof.

Fig. 1 is a perspective view of a combined cigarette extinguisher and handle for an ash receiver, showing our new design;

Fig. 2 is a side elevational view thereof;

Fig. 3 is a back end view thereof, looking at the right end in Fig. 2; and

Fig. 4 is a front view thereof, looking at the left end in Fig. 2.

The dotted line showing of an ash tray in Figs. 1 and 2 is for illustrative purposes only.

We claim:

The ornamental design for a combined cigarette extinguisher and handle for an ash receiver, substantially as shown and described.

DOUGLAS C. MACNALLY.
LAWRENCE S. BERDAHL.
